(57) **CLAIM**

We claim the ornamental designs for a LED troffer, as shown and described.

DESCRIPTION

FIG. 1 is a bottom view showing an embodiment of our new design for a LED troffer;

FIG. 2 is a front view of the LED troffer of FIG. 1;

FIG. 3 is a back view of the LED troffer of FIG. 1;

FIG. 4 is a left side view of the LED troffer of FIG. 1;

FIG. 5 is a right side view of the LED troffer of FIG. 1;

FIG. 6 is a top view of the LED troffer of FIG. 1;

FIG. 7 is a bottom perspective view of the LED troffer of FIG. 1;

FIG. 8 is a top perspective view of the LED troffer of FIG. 1;

FIG. 9 is a bottom view showing another embodiment of our new design for a LED troffer;

FIG. 10 is a front view of the LED troffer of FIG. 9;

FIG. 11 is a back view of the LED troffer of FIG. 9;

FIG. 12 is a left side view of the LED troffer of FIG. 9;

FIG. 13 is a right side view of the LED troffer of FIG. 9;

FIG. 14 is a top view of the LED troffer of FIG. 9;

FIG. 15 is a bottom perspective view of the LED troffer of FIG. 9;

FIG. 16 is a top perspective view of the LED troffer of FIG. 9;

FIG. 17 is a bottom view showing another embodiment of our new design for a LED troffer as viewed in use when mounted in a ceiling;

FIG. 18 is a front view of the LED troffer of FIG. 17;

FIG. 19 is a back view of the LED troffer of FIG. 17;

FIG. 20 is a left side view of the LED troffer of FIG. 17;

FIG. 21 is a right side view of the LED troffer of FIG. 17;

FIG. 22 is a top view of the LED troffer of FIG. 17;

FIG. 23 is a bottom perspective view of the LED troffer of FIG. 17; and,

FIG. 24 is a top perspective view of the LED troffer of FIG. 17.

(Continued)

The portions shown in broken lines are not part of the claimed design but show the environment in which the design is associated.
